United States Patent Office

Des. 193,343
Patented Aug. 7, 1962

193,343

VOICE REFLECTOR

Carolyn H. MacFarlane, 2926 Avalon Ave.,
Berkeley, Calif.

Filed Feb. 28, 1962, Ser. No. 69,024

Term of patent 14 years

(Cl. D25—1)

Fig. 1

Fig. 2

Fig. 3

FIGURE 1 is a perspective view looking from above and one side of a speech reflector showing my design;

FIGURE 2 is a perspective view looking from the front and above; and

FIGURE 3 is an elevational view of the side opposite that shown in FIGURE 1.

I claim:

The ornamental design for a voice reflector, substantially as shown.
